UNITED STATES PATENT OFFICE.

ROBERT MACDONALD, OF SCHENECTADY, NEW YORK, ASSIGNOR, BY MESNE ASSIGNMENTS, TO FREDERICK W. MANGOLD, OF SCHENECTADY, NEW YORK.

VULCANIZER.

1,410,693.

Specification of Letters Patent. Patented Mar. 28, 1922.

Application filed April 12, 1919. Serial No. 289,539.

To all whom it may concern:

Be it known that I, ROBERT MACDONALD, a citizen of the United States, residing at Schenectady, county of Schenectady, and State of New York, have invented certain new and useful Improvements in Vulcanizers, of which the following is a specification.

Reference may be had to the accompanying drawing, and the reference characters marked thereon, which form a part of this specification. Similar characters refer to similar parts in the several figures therein.

This invention relates to portable vulcanizers adapted for making repairs to the inner tubes of pneumatic tires and similar articles.

The principal object of the invention is to provide in compact portable form, a vulcanizer adapted for the repair of cuts extending in various directions, in an inner tube of a pneumatic tire or the like.

Other objects will appear in connection with the following description.

Fig. 1 of the drawing is a top plan view of my improved vulcanizer.

Fig. 2 is a central vertical longitudinal section of the same.

Fig. 3 is a view in perspective of a vulcanizing element for the use of which my improved vulcanizer is particularly adapted.

Fig. 4 is a central vertical longitudinal section of the same.

Referring to the drawings wherein the invention is shown in preferred form, 1 is a base-plate of elongated form, and 2 is an arm extending longitudinally of, and overhanging, the base-plate, 1, to which it is hinged at one end at 3.

The other end of the base-plate, 1, is provided with an open slot, 4, and the other end of the arm, 2, has pivoted thereupon at 5, a yoke, 6, through which extends a screw-bolt, 7, having on its lower screw-threaded end a wing-nut, 8, said screw-threaded portion of the bolt being adapted to swing into and out of the open slot, 4, and the wing-nut, 8, to be screwed into engagement with the bottom of the base-plate, 1, when the screw-bolt is within the slot, 4.

Rotatively mounted at 9 on the base-plate, 1, is a clamp-member, 10, in the form of an elongated plate adapted, for storage or transportation, to occupy a position extending longitudinally of the base-plate, 1, while

being adapted in use to be rotatively adjusted in any desired angular position with respect to the plate, 1.

A cooperative clamp-member, 11, in the form of a spider is rotatively mounted at 12, upon the arm, 2, said spider having two oppositely projecting legs, 13, longer than its other legs, the diameter of the spider measured along the legs, 13, being substantially equal to the long diameter of the clamp-plate, 10, while the shorter diameter of the spider is substantially equal to the shorter diameter of the clamp-plate, 10.

The spider, as well as the clamp-plate, 10, can thus be arranged with its longer diameter extending longitudinally of the base-plate, 1, for convenience in transportation and storage and when both of said clamp-members, 10 and 11, are thus arranged, they require a space no greater in width than that required by the base-plate, 1.

For certain purposes of the invention, the form of the several clamp-members, 10 and 11, may be varied within the scope of the appended claims.

I have shown a preferred form of clamp-member, 11, suitable for use with a vulcanizing element shown in Figs. 3 and 4, comprising a pan, 14, containing combustible material, 15, and bearing on its bottom a patch, 16, adapted for making the repair.

No claim is made herein to such a vulcanizing element, such elements being supplied to the trade in various forms and sizes.

The spider, 11, is adapted to cooperate with such vulcanizing elements when placed in various positions upon a flattened inner tube which rests upon the clamp-plate, 10, at substantially right angles to the base-plate, 1.

In the use of the device, the tube to be repaired is placed upon the clamp-plate, 10, with the tube extending at substantially right angles to the base-plate, 1, and the clamp-plate, 10, is rotatively adjusted so that it extends longitudinally of the cut to be repaired, which cut is covered by a vulcanizing element of the type described which is arranged to extend longitudinally of the cut, and the clamping spider, 11, is rotatively adjusted so that its long diameter extends longitudinally of the clamp-plate, 10.

The arm, 2, is then swung downward to-

wards the base-plate, 1, the screw-bolt, 7, swung into the slot, 4, and the wing-nut, 8, is tightly screwed up to clamp the vulcanizing element against the upper side of the 5 inner tube with whatever force is desired.

The combustible material is then ignited, and serves to produce the necessary heat for vulcanization, as is well understood.

In the preferred form of my invention as 10 shown the legs of the spider, 11, are open or channeled on the under side, thus affording a substantial engagement with the upper side of the vulcanizing element while providing along the legs of the spider a flue- 15 space for the free passage of air to, and gases of combustion from, the combustible material, 15.

What I claim as new and desire to secure by Letters Patent is—

- 20 1. In a device of the class described and in combination, a base; an elongated clamp-plate rotatably mounted upon the base; an arm hinged to one end of said base overhanging the base; a clamping-member rotatably mounted upon said arm concentrically with said elongated clamp-plate, said clamp-plate and said clamping-member being mounted with freedom for similar movements each through an arc of substantially 25 180°; a screw-connection between the other end of said arm and the base.
2. In a device of the class described and in combination, a base having a clamp-member, and an overhanging arm; a clamp- 30 35 ing-spider mounted upon said arm having its legs channeled on the other side, and

means whereby said spider can be forced toward said clamping-member on the base.

3. In a device of the class described and in combination, an elongated base; an elongated clamp-plate rotatably mounted upon the base; an arm overhanging said base; a clamping spider rotatably mounted upon said arm, certain oppositely projecting legs of said spider being longer than its other 45 legs; and means whereby said spider can be forced toward said clamp-plate.

4. In a device of the class described and in combination, an elongated base; an elongated clamp-plate rotatably mounted upon 50 the base; an arm hinged to one end of said base overhanging the base; a clamping spider rotatably mounted upon said arm, certain oppositely projecting legs of said spider being longer than its other legs; and 55 a screw-connection between the other end of said arm and the base.

5. In a device of the class described and in combination, an elongated base; an elongated clamp-plate rotatably mounted upon 60 the base; an arm hinged to one end of said base overhanging said clamp-plate; a clamp-spider rotatably mounted upon said arm concentrically with said clamp-plate, said spider having legs channeled on the under- 65 side, certain oppositely projecting legs of the spider being longer than its other legs; and a screw-connection between the other end of said arm and the base.

In testimony whereof, I have hereunto set 70 my hand this 31st day of March, 1919.

ROBERT MACDONALD.
